UNITED STATES PATENT OFFICE.

HENRY G. DAWSON AND WILLIAM R. DAWSON, OF CHICAGO, ILLINOIS.

FIRE-GRADE FOR FIRE-PLACES.

SPECIFICATION forming part of Letters Patent No. 367,793, dated August 9, 1887.

Application filed April 16, 1887. Serial No. 234,992. (No model.)

To all whom it may concern:

Be it known that we, HENRY G. DAWSON and WILLIAM R. DAWSON, of Chicago, Illinois, have invented certain new and useful Improvements in Fire-Grates for Fire-Places or Furnaces, of which the following is a specification.

The invention relates to means for clearing the grate; and it consists of a sliding head supported beneath the grate and provided with spurs or beveled teeth projecting between the parallel bars, and adapted to agitate the coal above as the head is moved back and forth.

The accompanying drawings illustrate the invention.

Figure 1 is a top view of a common fire-place grate with the cleaner attached. Fig. 2 is a bottom view of the same. Fig. 3 is a section on line $x-x'$ of Fig. 2, looking toward the left. Fig. 4 is a central section of Fig. 2 on line $x'-x'$. Fig. 5 is a section of the grate without its frame on line $y-y'$ of Fig. 2. Fig. 6 is a perspective of a detail, showing a modification.

A designates the frame of the grate. B is the grate provided with open parallel slots b. The grate is pivoted to the frame at a, so as to be dumped. At the front edge it rests on ledges or stops a' on the frame, and is provided with a sliding bolt, b', adapted to catch under the frame to prevent accidental tilting. The parts thus far described are of ordinary construction.

C is the rod or head, which is supported immediately beneath the grate in slots or ways c, so as to slide back and forth under it, and pro-

vided with a rod or handle, c', forked and attached at two points to the head, so as to move both ends of the same equally. The head is also provided with spur-wheels fitted loosely thereon, so as to turn freely, and projecting 40 through the slots of the grate and extending above the upper surface thereof, so as to come in contact with the coal. As the head is moved back and forth the spurs will rotate and agitate the bottom layers of coal, thus causing 45 the ashes to be separated therefrom and fall through the grate.

Fig. 6 shows the head C' provided with rigid teeth c', adapted to pass between the slots of the grate and agitate the coal as the head is 50 moved back and forth. This form may be used in place of the one provided with the spur-wheels; but the latter is the preferable one.

What we claim is—

1. The combination, with a grate, B, of a sliding head supported under the grate, and provided with teeth projecting through the slots b and movable therein, substantially as specified.

2. The combination, with a grate, B, of a sliding head, C, provided with rotary spur-wheels c', projecting through the slots b and movable therein, substantially as specified.

Chicago, April 11, 1887.

HENRY G. DAWSON.
WILLIAM R. DAWSON.
